GAME BOARD AND PLAYING PIECES FOR USE WITH THE SAME

Calvin D. Dunbar, Houston, Tex.

Application January 29, 1954, Serial No. 407,061

3 Claims. (Cl. 273—136)

This invention relates to a game board and playing pieces for the same, and more particularly to a spelling game and an improved game board and playing pieces for use in playing the same.

The invention has for its chief object the provision of an improved game board and playing pieces for use therewith, for the playing of a game in which playing pieces are positioned on the board to spell out various words, and in which the playing board and game pieces cooperate to facilitate the playing of the game.

Another object of the invention is to provide game apparatus of the type mentioned wherein the playing pieces are constructed and cooperate with the playing board in a manner to improve the visibility of the indicia employed in the playing of the game.

A further object of the invention is the provision of game apparatus of the kind mentioned wherein the playing board and game pieces are so constructed that the game pieces are always oriented in the same manner with relation to the game board during the playing of the game.

A still further object of the invention is to provide game apparatus which is of simple design and rugged construction, and which may be easily manufactured.

The above and other important objects and advantages of the invention will best be understood from the following detailed description, constituting a specification of the same, when considered in conjunction with the annexed drawings, wherein—

Figure 1 is a top plan view of a preferred form of the playing board of the invention;

Figure 2 is a fragmentary side elevational view, on an enlarged scale, showing the manner in which the playing board may be formed in sections, hingedly secured together, and illustrating the manner in which the board may be unfolded for use and folded up for purposes of storage or transportation;

Figure 3 is a fragmentary cross-sectional view, on an enlarged scale, taken along the line 3—3 of Figure 1, looking in the direction indicated by the arrows, and showing details of construction of the playing board and illustrating the manner in which the playing pieces are constructed for cooperation therewith;

Figure 4 is a top plan view, on a somewhat enlarged scale, illustrating a preferred form of playing pieces in accordance with the invention;

Figure 5 is a cross-sectional view, taken along the line 5—5 of Figure 4, looking in the direction indicated by the arrows;

Figure 6 is a fragmentary cross-sectional view, similar to that of Figure 3, illustrating a somewhat modified form of the game board and playing pieces; and

Figure 7 is a side elevational view, on a somewhat enlarged scale showing details of construction of the playing piece of the modified form of the invention illustrated in Figure 6.

Referring now to the drawings in greater detail the invention, briefly described, comprises a playing board,

2

generally indicated at 10, which may conveniently be of generally rectangular configuration, laid off in rows of polygonal areas, such as those indicated at 12, upon which playing pieces are adapted to be arranged, each of the playing pieces bearing a letter of the alphabet, and the game being played in a manner to spell out words by arranging the playing pieces in rows.

The playing board 10 is preferably formed with a rectangular central playing area, designated at 14, which is bordered on its four sides by auxiliary rectangular areas, designated 16, within which the playing pieces of the individual players are placed at the commencement of the game. The central playing area 14, in the present illustration contains 144 of the small rectangular areas 12 which are each adapted to receive a playing piece, while each of the auxiliary rectangular areas 16 is made up of 36 such areas 12, adapted to contain the playing pieces of the individual players. Thus, the central rectangular playing area is of sufficient size to contain all of the playing pieces of the individual players combined.

The playing board laid out in the manner described above is formed with depressions or upwardly opening recesses 18, one such recess in each of the small rectangular areas 12, the recesses being preferably of rectangular shape, as viewed in plan, and having their sides sloping inwardly and downwardly, as best seen in Figure 3 of the drawings.

The playing pieces used in playing the game are preferably constructed in the manner indicated in Figures 3, 4 and 5, each playing piece 20 being of generally inverted pyramidal shape, shaped to correspond to the depressions of recesses 18 of the board, and adapted to be positioned in the recesses. The playing pieces are preferably formed with flat bottom surfaces 22 adapted to seat on the bottom walls 24 of the recesses 18, and are formed with corner projections 26, which extend beyond the recesses 18, and are positioned to engage the surface of the playing board between the recesses, so that the pieces may be easily picked up from the board by grasping the pieces with the fingers by their opposite sides between the corner projections.

The playing pieces 20 are also formed with upwardly opening recesses or depressions 28, having rectangular bottom walls 30, and upwardly and outwardly sloping side walls 32, each wall of the recess 28 bearing the same letter of the alphabet, as indicated at 34 and 36. It will be apparent that by thus forming the playing pieces the letters 34 and 36, or other indicia employed, will be properly oriented relative to each of the individual players, so that it can be easily seen from any side of the game board. Because of the sloping of the walls 32 of the recesses 28, the letters 36 are presented in planes which make them more easily observed than would be the case if the letter 34 alone were employed, and such arrangement also presents the advantage that the letter observed by each of the individual players is properly oriented and is right side up as viewed by him.

By forming the playing board in sections, which are hingedly secured together, as indicated at 40, in Figure 2, the various sections may be folded upon each other with the playing pieces positioned in the recesses 18, if desired, whereby the apparatus is formed into a compact unit with the playing pieces contained therein, in the manner illustrated in Figure 2, for convenient carrying about.

In making use of the game apparatus, constructed as described above, the playing board is unfolded and laid out in the manner illustrated in Figure 1, and each player is provided with a set of playing pieces containing an entire alphabet with a suitable number of extra letters, which pieces are positioned in the auxiliary side areas 16 preparatory to the commencement of the game. Each

player may then place one of his playing pieces in the recess of one of the small areas 12 of the central playing area 14 and by taking turns the players may spell out various words by placing additional playing pieces in the various rows of the playing area of the board. The game, of course, may be played in a number of different ways, and in accordance with any desired rules, as may be expedient or conducive to the amusement and entertainment of the players.

In Figures 6 and 7 a somewhat modified form of the invention is illustrated, wherein the playing board 10' may be laid out in a manner similar to that described in connection with the invention as illustrated in Figure 1. In this form of the invention, however, the playing area and the auxiliary side areas bordering the same may be provided with projections 42, instead of the depressions 18 of the previously described form of the invention, over which projections playing pieces 20' are adapted to be positioned, to retain the playing pieces in properly oriented positions relative to each of the players. The playing pieces 20' are preferably of pyramidal shape, and of a size to fit snugly on the projections 42. Each of the sides of the playing pieces 20' is provided on its exterior with a letter of the alphabet, as indicated at 32' so that in playing the game one letter of each playing piece will be positioned for convenient observation by each of the players and will be properly oriented or upright relative to him. In other respects the playing board 10' is substantially the same as the board 10 of the previously described form of the invention.

By suitably hinging the sections of the boards 10' together the sections may be folded in a manner similar to that previously described with the playing pieces 20' in position on the projections 42; whereby the apparatus may be folded into a compact unit for carrying about, with the playing pieces contained therein.

It will thus be seen that the invention, as described above, provides game apparatus for the playing of spelling games or the like, which is of simple design, and in which the board and game pieces are constructed to provide improved visibility and cooperate in a manner to assure proper orientation of the parts at all times.

The invention has been disclosed herein in connection with certain specific embodiments of the same, but it will be understood that this is intended by way of illustration only, and that numerous changes can be made in the particular design and arrangement of the game board and playing pieces, without departing from the spirit of the invention or the scope of the appended claims.

Having thus clearly shown and described the invention, what is claimed as new and desired to secure by Letters Patent is:

1. Game apparatus comprising a game board having a playing surface and formed with a plurality of spaced apart playing areas, each having a bottom portion of polygonal shape disposed in parallel spaced relation to said surface and sloping side walls extending between said portion and said surface, hollow, open-topped, game pieces each having side walls shaped to fit the sides of said areas, said sides having identical letters of the alphabet thereon in position to be seen in any position of the pieces on said areas.
2. Game apparatus comprising a game board having a playing surface and formed with a plurality of spaced apart depressions forming playing areas each having a bottom portion disposed in parallel spaced relation to said surface and sloping sides extending between said portion and said surface, hollow, open-topped game pieces having side walls shaped to conform to the sides of said areas, said game pieces being engageable with the board in said depressions to hold said walls in parallel relation to said sides, each of said sides having a letter of the alphabet on the interior thereof in position to be visible through the top of the piece.
3. Game apparatus comprising a game board having a playing surface and formed with a plurality of spaced apart areas of polygonal shape and an upwardly extending projection in each of said areas conforming to the shape of the area and having upwardly converging sides, hollow game pieces having side walls shaped to conform to the sides of said areas and which slope upwardly and inwardly from the lower end of the game piece, said game pieces being engageable with said projection to hold said walls in parallel relation to said sides, each of said side walls having a letter of the alphabet on the exterior thereof.
